UNITED STATES PATENT OFFICE.

FREDERICK KOHNLE, OF DAYTON, OHIO, ASSIGNOR TO THE MONARCH MARKING SYSTEM, OF DAYTON, OHIO, A CORPORATION OF OHIO.

PRICE TAG.

Application filed February 19, 1925. Serial No. 10,380.

This invention relates to a pin-attached merchandise marking tag as an article of manufacture or product wherein the commercial pin with pointed and headed opposite ends is utilized for securing the tag to the merchandise. The pin is deformed to provide a crimp or bend at its point end to restrain accidental withdrawal from the tag and merchandise and the point of the pin 5 angled in a direction to pierce into the tag, preferably into the underside of the tag, for guarding the point. The deforming of the pin is preferably accomplished in its application to the tag and merchandise following 10 the method set forth and made the subject matter of a separate application filed by me on May 12th, 1923, and patented March 3, 1925, No. 1,528,023.

This method is susceptible to machine operations for quickly and efficiently engaging the pin through the tag and merchandise and at the same time crimping or bending the pin to anchor it against accidental withdrawal and pierce the point into the tag to 25 guard the same or conceal the point between the underside of the tag and adjacent face side of the merchandise and angled so that it will not penetrate through either the tag or merchandise.

30 Many different types of metallic fasteners in the form of wire clips and staples have been employed for securing price tags upon fabric merchandise, all of which in some degree have been found objectionable, either 35 as readily susceptible to corrosion, unadapted for use in conjunction with a tag marking and applying machine, difficult to remove by the user without injury to the hands or goods, or their point ends too blunt to 40 pass through a certain quality of goods without injury to the fibre of the goods, and as the fasteners generally were combined with the tag it is not feasible under prevailing methods of manufacture for rapid and economical production to highly surface finish 45 the fastener to serve as the commercial or common pin. The common pin is made under very highly developed processes of manufacture and of such common usage that 50 everyone understands how to remove the pin in a correct manner.

It represents a very small gauge round wire material with appropriate stability and rigidity having a long tapering and fine 55 pointed end for easy piercing through the

material to which it is to be applied and thus can be attached to the finest woven fabric material without drawing or permanently separating the threads. Its entire surface is highly polished and preserved against corrosion and its headed end facilitates its insertion or removal to and from the tag and merchandise and is also of a structure very applicable for use for tag machine application. 60 65

It is therefore an object of the invention to utilize the commercial pin as a fastener for securing a tag to fabric merchandise with the pin having a crimped or bent portion preferably toward the point end thereof to 70 withhold the pin against accidental removal when applied and with the point angled or extended in an inclined direction to prick into the tag so that the point will be guarded and protected and which can be removed by 75 the user without injury to the goods.

Further advantages and features of the invention will be more fully set forth in the description of the accompanying drawings forming a part of this specification in which: 80

Figure 1 is a plan view of a tag as applied to a piece of fabric merchandise with a commercial pin deformed to possess the characteristics heretofore mentioned.

Figure 2 is a section on line 2-2, of 85 Fig. 1.

Figure 3 is an enlarged detail sectional view of parts of a tag machine for applying the pin to the tag and merchandise and for crimping and bending the point end of 90 the pin to properly anchor the same and to project the pin point into the body of the tag from the outside thereof.

Figure 4 is a modification of tag providing an aperture for receiving the head of 95 the pin when applied.

As the method of applying the pin to the tag and merchandise is preferably practiced in connection with a tag marking machine, it is preferable to describe the invention in 100 such capacity of use. The tags usually are arranged in gang or strip length and provisioned for step feeding so that they may be successively operated upon and moved between cooperating die and anvil members 105 for appropriately supporting and conditioning the tag and merchandise to receive the pin adapting the pin to be engaged through and through the goods and tag several times in an approximate longitudinal direction 110

and deformed for appropriately securing the pin in position and protecting the point thereof.

Thus in Fig. 3 the tag 1 and fabric merchandise 2 through which the pin 3 is engaged is shown as inserted between a die plate 4 and an anvil headed plunger 5, the die being rigidly mounted and the plunger adapted to be reciprocated toward and from the die plate, the mechanism for operating the plunger however herein not disclosed.

The die plate is shown as recessed and the anvil correspondingly rounded to press the tag and goods therebetween into bowed or curved form so that the pin can be passed longitudinally through the tag and goods several times preferably initially entering from the face side of the tag so that the head of the pin will be exposed to such side of the tag and accessible for engagement when it is desired to remove the pin from the tag and goods. The pin is shown as passing through the tag and goods and thence from the reverse or lower side of the goods again passing through the goods and tag to the face side of the tag and thence from the face side of the tag through the tag with the point inclined or bent to prick or pierce into the tag, and preferably to a degree which will not pass completely through the tag. The pin passes through a channel or groove 6 in the head end of the plunger so as to properly guide the same to engage into a pin bending recess 7 formed in the die plate for crimping or bending the forward or point end and to direct the same downwardly through the tag and into engagement with the guide plate 8 beneath the tag by directing and bending the point of the pin upwardly or to an angle or incline to pierce into the underside of the tag concealing and guarding the point within the ply thickness of the tag, or, if the ply of the tag is too thin to imbed the point therein, to bring the point between the lower side of the tag and adjacent side of the fabric secured to the tag.

The downward crimping gives the point end portion a slight hook bend sufficient to

anchor the pin against accidental withdrawal in the handling of the ticketed goods. The bowing of the tag and goods is to a degree sufficient to enable the pin to pass through the tag and goods several times in a straight line with the head exposed on the face side of the tag and the point imbedded into the tag body either from the face or underside of the tag and which will not permit the pin point to be extracted with any yield of the tag when released from between the anvil and die. The pin preferably is inserted medially of the tag with the head of the pin at the head of the tag as offering the best position for securely fastening the tag to the goods and the tag being slightly bowed is thus reinforced to sustain the opposite side of the tag against upward lapping or flexing, nor does the pin produce a line along which the tag can be readily torn or bent.

Forming the crimp at the point end of the pin adapts the same to be located at a free end of the tag. It however is obvious that the pin could be otherwise crimped or bent if a more permanent anchoring is required.

The drawings show the pin crimp slightly exaggerated for the purpose of illustration. The crimp or corrugations of the pin in the product are of such degree of arch which provide for the pin contact against the tag surfaces, so as not to form too great an obstruction to pin withdrawal, although for some uses the corrugations can be very pronounced.

Having described my invention, I claim:

A merchandise price marking tag comprising a tag, and a commercial pin having pointed and headed relatively opposite ends, the pin engaged through the tag and merchandise and the point end of the pin crimped to extend through the tag only from the face side thereof and direct the point at an angle against the underside of the tag, with the crimp of a character to restrain accidental withdrawal of the pin.

In witness whereof, I hereunto subscribe my name.

FREDERICK KOHNLE.
